UNITED STATES PATENT OFFICE

AUGUST DLOUHY, OF WALLINGFORD, CONNECTICUT

DESIGN FOR A CURTAIN ROD END

Application filed November 23, 1931. Serial No. 41,829. Term of patent 3½ years.

To all whom it may concern:

Be it known that I, AUGUST DLOUHY, a citizen of the United States, residing at Wallingford, in the county of New Haven and State of Connecticut, have invented a new, original, and ornamental Design for a Curtain Rod End, of which the following is a specification, reference being had to the accompanying drawings, forming part thereof, in which—

Fig. 1 is a front view of a curtain rod end showing my new design;

Fig. 2 is a central sectional view through Fig. 1.

I claim:

The ornamental design for a curtain rod end, substantially as shown.

AUGUST DLOUHY.
